UNITED STATES PATENT OFFICE.

FREDERICK ARTHUR SMITH, OF BRASTED, ENGLAND.

IGNITION DEVICE FOR INTERNAL-COMBUSTION ENGINES.

1,422,794.

Specification of Letters Patent. Patented July 11, 1922.

Application filed January 19, 1920. Serial No. 352,425.

To all whom it may concern:

Be it known that I, FREDERICK ARTHUR SMITH, subject of the King of England, residing at Brasted, Kent, England, have invented certain new and useful Improvements in Ignition Devices for Internal-Combustion Engines, of which the following is a specification.

This invention relates to ignition-devices for internal-combustion engines of the kind in which an ignition-chamber forming an annex to and communicating with the engine-cylinder has ignition-charges of, say, air and petrol-vapour delivered into it from a fuel-supply conduit deriving its supply from a carburettor or other source external to the engine-cylinder, each ignition-charge being ignited in the ignition-chamber and issuing, after ignition, as a spurt of flame 20 into the engine-cylinder to ignite the main charge therein.

The principal object of the present invention is to provide for an internal combustion engine an automatic regulating-device for the purpose of delivering the ignition-charge (or even the sole combustible charge should the usual main charge to the engine be cut off and the ignition-charge thus become the only charge) to the engine, efficiently and economically under varying working-conditions, said device to be interposed between the ignition-chamber and the source of supply of the ignition or other charge, and preferably as near as possible to the ignition-chamber, which automatic regulating-device shall comprise a box, such for instance as is hereinafter described, fitted with a valve or valves, which box intercepts the engine-suction and which is so constructed that it will either (a) prevent the engine-suction from having at the time at which the piston sets it up, any direct access to the source of ignition-charge or, alternatively, (b) limit the effect of the engine-suction on the ignition-charge to a low degree, and in either case will (c) accumulate in the interval following a suction-stroke, the whole or the major part of the ignition-charge for the next succeeding suction-stroke.

In the first case the engine is limited to a draught during the suction-period upon the contents of what is actually or virtually a closed box, instead of making an unchecked draught through any supply passage leading

uninterruptedly in the usual manner at full bore back from the cylinder to the prime source of ignition charge; this mode of limitation has been found to ensure economical use of the ignition charge and also the retention in the upper end of the ignition-chamber of a portion of the ignition-charge which is pure and uncontaminated and is therefore adapted to ignite promptly and efficiently and thus to do its full share in the efficient working of the engine as a whole. It will do this with different ignition-fluids and with main charges in the engine that are weak or that otherwise (as by reason of the nature of the fuel-supply) would be difficult of ignition.

In the second case the action is virtually the same because although the supply-pipe to the box during the suction period stroke is open it is to be restricted in bore to such a degree that it shall not be able to replace in the box during the short time taken by the suction that part of the contents which is then removed from the box, but shall only be able to replace it in the much longer interval which occurs between the suction-periods.

In either case the box will deliver, upon the opening of the delivery-valve of the box an ignition-charge which consists either wholly or for the most part, of the contents of the box accumulated therein during the intervals between the suction-strokes.

A complete or partial closure of this box, intercepting the engine-suction as aforesaid, prevents any such extreme variations of flow from the source of ignition-charge to the ignition-chamber as have occurred in former cases in which the communication between the engine-cylinder and the source of ignition-charge has been unimpeded.

In multiple-cylinder engines wherein there has been direct and unimpeded communication between the several cylinders and their source of ignition-charge it has frequently happened that the connection from one cylinder has been able to draw more supply to that cylinder than its proper share; now with the interrupted or impeded and accumulative flow in the device herein described, each cylinder to which the device is applied will get substantially its proper amount of ignition-charge.

The automatic regulating-device in addition prevents the back-pressure of the

ignition and explosion from being communicated to the source of ignition-charge aforesaid.

Further objects of the present invention 5 are to combine with an automatic regulating-device of the kind above referred to, an improved ignition-chamber formed as a plurality of communicating vessels leading in series from the said regulating-device to the 10 engine-cylinder and so shaped and proportioned as to ensure an efficient production of flame and good subsequent projection thereof into the main charge in the engine and also to act in certain cases as a regenerative 15 heater or vaporizer for the fuel and air in its neighbourhood.

According to the present invention there is combined with the engine-cylinder an automatic regulating-device which comprises 20 a box interposed between the ignition-chamber and the source of supply of the ignition-charge and to which box a fuel-supply conduit leads the fluid which is to be used for the igniting charges. From this box a delivery-conduit constituted by the ignition-chamber leads to the interior of the engine-cylinder; and in this delivery conduit there is a delivery-valve so constructed and arranged as to be opened and shut as a consequence of variations in pressure in the interior of the engine cylinder. Conveniently the arrangement is such that apart from its weight, the said delivery-valve is operated 30 solely by the fluid pressure existing on its opposite sides which communicate respectively with the interior of the engine cylinder and of the box. Or the delivery-valve may be combined with means (for example a spring or a weight) which tend always to 35 keep it shut, but which will yield and permit it to open whenever the fluid-pressure in the interior of the engine-cylinder falls sufficiently low in relation to the fluid-pressure in the box aforesaid to enable the latter 40 pressure to overcome the spring or weight aforesaid. The valve opens automatically during each suction stroke of the engine and is so constructed that it will not open to any 45 back-pressure from the engine-cylinder or the ignition-chamber. The source of supply may be under super-atmospheric pressure, if desired; but such pressure must not be high enough to overcome of itself the 50 spring or weight aforesaid. Moreover, it is an important feature of the present invention that in the fuel-supply conduit leading the fluid for the ignition-charges to the interior of the box aforesaid there are means which shall ensure by stoppage or wire-drawing of the influx that whilst as a consequence of the opening of the delivery-valve evacuation from the said box is occurring, an entry of as much fluid by the fuel-supply conduit as the quantity evacuated 55 from the box shall be prevented from occurring.

This preventive means may be a fuel-supply valve in the fuel-supply conduit as hereinafter described, which valve will prevent the suction in the engine-cylinder from reaching at any rate at its full value 70 the source of supply of the ignition-charges; or if the valve is absent, the means may consist of a constricted fuel supply conduit whereby the effect of the suction in the engine-cylinder upon the source of the ignition 75 charges may be minimized to a degree which is not injurious to the efficiency of the engine; or the valve and a constricted fuel-supply conduit may be used conjointly as will hereinafter appear. 80

To the automatic regulating-device aforesaid there may be added the kind of ignition-chamber hereinafter exemplified.

According to another feature of the invention a single box, preferably formed as 85 an element which is separate from the engine cylinders, supplies more than one cylinder. Such a box may enclose the regulating means governing the flow through the fuel supply conduit. Compactness of construction will thus be secured. 90

For a more complete understanding of the invention there will now be described with reference to the accompanying drawings, and by way of example only, certain constructional forms of ignition device according to the present invention. It is to be understood, however, that the invention is not limited to the precise details enumerated. 95

In these drawings:— 100

Figure 1 is a vertical central section of one construction of automatic regulating-device and ignition-chamber according to the present invention with a portion of the upper end of an engine-cylinder to which 105 they are attached;

Figure 2 is a similar view of an alternative construction thereof;

Figure 3 is a view of the upper part of Figure 1 modified as hereinafter described; 110

Figure 4 is a diagrammatic sectional elevation to illustrate the application of a modification akin to that which is shown in Figure 3 to a multi-cylinder engine;

Figure 5 is a section through a construction of ignition device corresponding more or less exactly to the construction shown in Figure 2. 115

Figure 6 is an enlarged view of a portion of Figure 5;

Figure 7 is a cross-section on the line 7—7 of Figure 6. 120

Figure 8 is a section through another construction of ignition device; and

Figure 9 is a section through a further 125 construction of ignition device, corresponding in some respects to the construction shown in Figure 4.

Like reference letters indicate like parts throughout the figures. 130

With reference first to Figure 1:—

Above the engine-cylinder E is a box B. A fuel-supply conduit FSC leads to the interior of the box B from any convenient 5 source of fluid ignition-charges. A delivery-conduit DC leads from the box B to the interior of the engine-cylinder E, preferably projecting at its lower end DC¹ into the cylinder, as shown.

10 In and controlling the delivery-conduit is a non-return delivery-valve DV opening downwardly and fixed to the lower end of a rigid rod R, to the upper end of which rod is secured a fuel-supply valve FSV in 15 and controlling the fuel-supply conduit FSC, into which it opens upwardly. The valve FSV is screwed on to a threaded portion of the rod R and can therefore be adjusted up or down in relation to the rod if 20 desired. A nut N holds the valve FSV in the position on the rod R to which it is adjusted.

The valve DV is held on the rod R at such a distance from the valve FSV thereon that 25 when the latter is in closed position the rod R will hold the former open and vice versa.

A spring S bearing at its lower end on the 30 top of a part of the fuel-supply conduit and at its upper end on a head H carried by the rod R tends always to maintain the rod R and valves FSV and DV in a position in which the delivery-valve DV is shut and the fuel-supply valve FSV open. The head H 35 is threaded on to the rod R so that it may be adjusted thereon to regulate to the desired degree the compression of the spring S.

As soon as the reduction of pressure in the 40 engine-cylinder E during the suction stroke is sufficient to enable such fluid-pressure as exists in the box B to force down the valve DV against the resistance of the spring S (which will have been adjusted accordingly), that valve will open, and in opening will 45 shut down or partially shut down the valve FSV. Thereupon the contents of the box B or part of them will expand into the delivery-conduit DC, which thus obtain a sufficiency of charge for the next ignition. 50 The valve FSV being shut or partly shut, flow into the box B along the conduit FSC is stopped or impeded. The charge expanded as described into the delivery-conduit DC is (after compression by the action 55 of the engine-piston) ignited, the pressure in that conduit having previously risen and cooperated with the spring S in shutting the valve DV, thus not only preventing the compression and the back-pressure of the ignition 60 and explosion from being communicated to the fuel-supply conduit aforesaid but simultaneously opening the valve FSV. On the opening of this valve, further ignition-charge passes from FSC into B to re- 65 store the pressure therein which was previ-

ously lowered when part of the contents of B were evacuated through DV whilst the latter was open.

During and after this restoration of pressure in B the valve DV remains closed until 70 engine suction again opens it in the manner above described.

It will be seen that in any one suction-stroke of the engine the delivery-conduit DC can only obtain charge from below the 75 closed or partially closed fuel-supply valve FSV, for when suction is strong there is practically (or actually, as the weakness of the spring S may determine) no through flow from FSC into B during the suction- 80 stroke.

Referring now to Figure 2, the fuel-supply conduit FSC has no valve in it, but is constricted as at C (or it might be of small bore throughout its length to produce an 85 effect substantially the same as though it were narrowed at one place only).

The valve DV, rod R and spring S are substantially the same as in Figure 1, except that the spring rests on a spider s inside the 90 box B, which spider serves also as a guide for the rod R.

In Figure 2 as soon as the reduction of pressure in the engine-cylinder E during the suction stroke is sufficient to enable such 95 fluid pressure as exists in the box B to force down the valve DV against the resistance of the spring S, that valve will open and the contents of the box B or part of it will expand into the delivery-conduit DC. Although the flow into the box B along the conduit FSC is not altogether stopped (as it was in Figure 1 in the case in which FSV was shut) during the time that the valve DV remains open, the flow past the constriction 100 C is at all times when DV is open, to be so wire-drawn that the entry of fluid in this period will not balance, in quantity, that evacuated by way of the valve DV. Such balance will ultimately be restored, but not 110 till after the valve DV has been shut by the joint action of the spring S and the compression ignition and explosion pressure, as in Figure 1. Consequently while the valve DV in Figure 2 is open, though the engine- 115 suction modified in degree by the presence of the box B may be operative on the contents of the fuel-supply conduit FSC, this will not injuriously affect the working of the engine because its effect will be reduced 120 by the constriction C to a level at which it will do no harm.

Referring now to Figure 3:—

If the construction illustrated in Figure 1 were altered as in Figure 3 by fixing a piston-valve FSP on the rod R in place of the poppet valve FSV of Figure 1 and by providing a cylindrical seating CS for it in which there is a port TP forming a constricted end for the fuel-supply conduit 130

FSC variable in area by the valve FSP, the altered construction would operate as follows:—

With the delivery valve DV open to a given extent, the piston-valve FSP if previously suitably set on the rod R relatively to the valve DV, would cover the port TP completely or, alternately, could be arranged to leave it slightly open, and if the amounts of opening of the delivery-valve were reduced below the given extent aforesaid, the piston-valve FSP would automatically increase, in inverse proportion, the amount of opening of the port TP. With such a means as this for varying the amount of the constriction of the fuel-supply conduit, such influx into B as occurs whilst DV is open is variable in relation to the movement of the valve DV so that the tendency of strong suction in the engine to draw an excessive amount of ignition-charge into the delivery-conduit DC is counteracted and moreover, the tendency of weaker suctions to draw too weak a charge into the delivery-conduit is also counteracted in degrees inversely proportioned to the weakening of the suction. The port TP may be tapered, as shown, or otherwise formed to facilitate the proportioning of the ignition-charges to the suction, as required.

Referring now to Figure 4, this illustrates an alternative construction according to the present invention wherein boxes B are applied one to each cylinder E¹ E² of a two-cylinder engine, but the fuel-supply conduits FSC¹ FSC² to the respective boxes are led to a valve-chamber VC common to them, which chamber derives its supply from the principal fuel-supply conduit FSC. In the valve-chamber is a piston-valve FSP on a rod R¹ normally held up by a spring S¹ and sliding over a cylindrical seating CS in which there are ports TP each forming a constricted end of variable effective area for the fuel-supply conduit FSC at its virtual junction with the fuel-supply conduits FSC¹ FSC². The valve FSP in Figure 4, however, instead of being moved by either of the delivery-valves DV according to the suction in any one cylinder E¹ or E², is actuated by a piston P in a cylinder SC in opposition to the action of the spring S¹. The piston P is itself operated by the suction exerted upon it from both the cylinders E¹ E² indirectly by a suction-pipe SPP leading from the common induction-pipe IP of both the cylinders E¹ E²; consequently the movements of the fuel-supply piston FSP are determined by the average suction of the engine.

In Figures 1 and 2 the delivery-conduit DC which extends from the delivery-valve DV to the engine-cylinder E is formed as a plurality of co-axial communicating chambers 1, 2 and 3 (Figure 1) or 1 and 2 (Figure 2) in series. The vessel 1 contains a spark-plug SP for firing the ignition charge. These

vessels are successively larger as they near the engine-cylinder and each is provided with a coned outlet CO having its narrower end directed towards the engine-cylinder. Baffles F project into the delivery-conduit between these vessels, to check back-flow up them, and to counteract the tendency of burnt and other gas from the cylinder to rise in the ignition-conduit and contaminate the plug.

In the first of these vessels (1 in the drawings) that is to say the vessel nearest the point of entry of the ignition-charges into the ignition-conduit the freshest part of the ignition-charge will be found. The capacity of this vessel 1 should be such that it will preferably not contain more than the bulk of the freshly admitted ignition-charge after that has been compressed; thereby, as well as by the baffles F, the risk of stale gas being forced up into it is minimized.

The projecting end DC¹ of the delivery-conduit DC gets hot and heats, regeneratively, the gases inside it, and outside it, thereby facilitating the ignition of the main charge in the engine-cylinder.

In the constructions of ignition-device described above the delivery-valve DV is fitted with a spring which tends always to keep it shut but which will yield and permit it to open whenever the fluid pressure in the interior of the engine cylinder falls sufficiently low. It is not, however, essential that the delivery valve should be provided with a spring or any other positive means for this purpose as it is possible for it to be operated, apart from its weight, solely by variations in pressure in the interior of the engine cylinder.

Referring now to Figures 5, 6 and 7, the delivery valve DV shown therein takes the form of a thin circular disc which is received in a cup G mounted in a boss H in the box B. The cup G is retained in position by a screwed and perforated cap J. The cup G is recessed at K to receive the valve DV and is slotted at L to provide a throughway from the interior of the box B to the chamber 1. The perforation J¹ in the cap J, and the delivery-valve DV are of such relative sizes that the delivery-valve when against the lower end of the cap J can completely close the end of the perforation J¹ and thus shut off communication between the box B and the chamber 1.

Its own weight will, of course, tend to keep the valve DV open, but this valve may be made of such thin metal that its weight will be negligible, and it can thus be operated solely by the fluid pressure existing on its opposite sides which communicate respectively with the interior of the engine cylinder and of the box B. Thus due to the variations in pressure, the valve DV will, during the inlet stroke of the engine piston, be open, and during the compression, firing and exhaust

strokes it will be shut, the pressure in the engine cylinder during each of these three latter strokes being higher than that in the box B.

- 5 The parts SP, DC, F, 2, E, DC¹, CO, C and FSC shown in these figures are the same as are shown in Figure 2.

Referring now to the construction shown in Figure 8, the parts E, B, and SP are similar to those described above, but it will be observed that the box B is separate from the engine cylinder. The sparking plug SP projects into a chamber LL leading through a conduit M to the interior of the cylinder. 10 Communicating with the chamber LL also are conduits N which can communicate through a conduit N¹ with a pipe PP leading from the box B. Controlling the conduit N¹ is the delivery-valve DV which in this construction takes the form of a ball, and it will be observed that by its own weight it tends to close the conduit N¹. Similarly to the construction shown in Figures 5 to 7, however, this delivery-valve will be opened and 15 shut by the variations in pressure on the opposite sides of it; that is to say it will be opened during the inlet stroke of the engine piston and closed during the compression, firing and exhaust strokes.

20 30 In the construction shown in Figure 9 the arrangement is in many respects the same as shown in Figure 4, and the parts E¹, FSC, FSC¹, FSC², FSP, P, S¹, SC, SPP, SP and 1, are the same. Included in the pipe SPP is a valve Z to cut off or modify the suction say when the engine is being run on the supply through the conduit FSC alone (i. e. the auxiliary supply). The conduit FSC¹ communicates with the chamber 1 25 through conduits N and N¹ whereof the latter may be closed by a ball delivery-valve DV. In this construction the weight of the delivery-valve DV will not operate either to open or to close the valve but the latter will 35 be operated solely by variations in pressure on the opposite sides of it. The conduits FSC¹ and FSC² draw their supplies from the box B which is formed as an element separate from the engine cylinders E¹. This 40 box B encloses the regulating means governing the flow from the supply conduit FSC to the conduits FSC¹ and FSC². The conduit FSC communicates with the box B through ports Q and it is controlled by the 45 valve FSP operated by the pressure in the pipe SPP. As only one cylinder at a time is drawing upon the box B, the effect is substantially the same as in the other constructions in which each cylinder has a separate 50 box. During the suction period of any one cylinder the latter has access to an accumulated charge to which there is a restrained influx of mixture. This construction as applied to multi-cylinder engines has the advantage of compactness of construction.

From the foregoing it will be observed that the constructions shown in Figures 5-9 operate on the same principle as the constructions shown in Figures 1-4 and offer the same advantages; they also offer other advantages. For instance the omission of spring loaded delivery valves is from some points of view desirable.

What I claim as my invention and desire to secure by Letters Patent is:—

1. An automatic charge-accumulating and regulating device for internal combustion engines, comprising a box, a fuel supply conduit leading thereto, a delivery conduit leading therefrom to the engine cylinder, said delivery conduit comprising a plurality of communicating chambers having baffles therebetween, a delivery valve in said delivery conduit adapted to be opened and shut by variations in pressure in the engine cylinder, and controlling means in the fuel supply conduit preventing the entry of as much fluid to the box as is evacuated therefrom while the delivery valve is open, substantially as described.

2. An automatic charge-accumulating and regulating device for internal combustion engines, comprising a box, a fuel supply conduit leading thereto, a delivery conduit leading therefrom to the engine cylinder, a springless delivery valve in said delivery conduit adapted to be operated by variations in pressure in said cylinder, and controlling means in the fuel supply conduit preventing the entry of as much fluid to the box as is evacuated therefrom while the delivery valve is open, substantially as described.

3. An automatic charge-accumulating and regulating device for multicylinder internal combustion engines, comprising a single box formed as an element which is separate from the engine cylinders, a fuel supply conduit leading thereto, a delivery conduit leading from said box to the interior of each engine cylinder, a delivery valve in each delivery conduit opened and shut by variations in pressure in the interior of the engine cylinder, and controlling means in the fuel supply conduit preventing the entry of as much fluid to the box as is evacuated therefrom while the delivery valve is open, said controlling means being surrounded by the said box, substantially as described.

4. In an internal combustion engine, an automatic charge-accumulating and regulating device, comprising the combination with a box, a fuel-supply conduit leading thereto, a delivery conduit leading from said box to the engine cylinder, and a delivery valve in the delivery conduit adapted to be opened and shut by variations in pressure in the interior of the engine-cylinder, the only action of suction in the cylinder on said valve being such as tends to open it, of fuel-supply controlling means in said fuel supply con-

duit arranged to prevent the entry of as much fluid into the box as is evacuated therefrom while the delivery valve is open, and thereby cause a greater reduction of pressure in said box and in the whole of said delivery conduit, when said delivery valve is opened by suction, than would obtain were the said controlling means not provided, substantially as described.

10 5. In an internal combustion engine, an automatic charge-accumulating and regulating device, comprising the combination with a box, a fuel-supply conduit leading thereto, a delivery conduit leading from 5 said box to the engine cylinder, and a delivery valve in the delivery conduit adapted to be opened and shut by variations in pressure in the interior of the engine-cylinder, the only action of suction in the cylinder 10 on said valve being such as tends to open it, of fuel-supply constricting means in said fuel-supply conduit arranged to prevent the entry of as much fluid into the box as is evacuated therefrom while the delivery 20 valve is open, and thereby cause a greater reduction of pressure in said box and in the whole of said delivery conduit, when said delivery valve is opened by suction than would obtain were the said constricting 25 means not provided, substantially as described.

6. In an internal combustion engine, an automatic charge-accumulating and regulating device, comprising the combination with a box, a fuel-supply conduit leading thereto, a delivery conduit leading from 35 said box to the engine-cylinder, and a delivery valve in the delivery conduit adapted to be opened and shut by variations in pressure in the interior of the engine cylinder, suction in the cylinder tending solely to open said valve, of fuel-supply throttling means in said fuel-supply conduit arranged to prevent the entry of as much fluid into 40 the box as is evacuated therefrom while the delivery valve is open, and thereby cause a greater reduction of pressure in said box and in the whole of said delivery conduit, when said delivery valve is opened by suction 45 than would obtain were the said throttling means not provided, substantially as described.

7. In an internal combustion engine, an automatic charge-accumulating and regulating device, comprising the combination with a box, a fuel-supply conduit leading thereto, a delivery conduit leading from said box to the engine-cylinder, and a delivery valve in the delivery conduit adapted to be 55 opened and shut by variations in pressure in the interior of the engine-cylinder, the only action of suction in the cylinder on said valve being such as tends to open it, of a fuel-supply valve for controlling said 60 fuel-supply conduit, which fuel-supply valve

is arranged to be subjected to the action of suction in the engine-cylinder when the delivery valve is open, in such manner that it tends to close the fuel-supply conduit under the action of such suction, substantially as 70 described.

8. In an internal combustion engine, an automatic charge-accumulating and regulating device, comprising the combination with a box, a fuel-supply conduit leading thereto, 75 a delivery conduit leading from said box to the engine cylinder, and a delivery valve in the delivery conduit adapted to be opened and shut by variations in pressure in the interior of the engine cylinder, the only 80 action of suction in the cylinder on said valve being such as tends to open it, of a fuel-supply valve arranged to control said fuel-supply conduit, and means controlled by variation of pressure in the cylinder, 85 which means are operatively connected with said fuel-supply valve and tend to close the latter under the action of the suction in the cylinder, substantially as described.

9. In an internal combustion engine, an 90 automatic charge-accumulating and regulating device, comprising the combination with a box, a fuel-supply conduit leading thereto, a delivery conduit leading from said box to the engine-cylinder, and a delivery valve 95 in the delivery conduit adapted to be opened and shut by variations in pressure in the interior of the engine-cylinder, the only action of suction in the cylinder on said valve being such as tends to open it, of fuel-supply controlling means in said fuel-supply conduit 100 arranged to prevent the entry of as much fluid into the box as is evacuated therefrom while the delivery valve is open, and thereby cause a greater reduction of pressure in 105 said box and in the whole of said delivery conduit, when said delivery valve is opened by suction, than would obtain were the said controlling means not provided, said delivery conduit comprising a plurality of 110 chambers opening one into another in a row, whereof the chamber nearest said box constitutes an ignition chamber, and ignition means in said ignition chamber, substantially as described.

10. In an internal combustion engine having a plurality of cylinders, an automatic charge-accumulating and regulating device comprising a box, a fuel-supply conduit leading thereto, a plurality of delivery conduits leading from said box to the interior of each of said cylinders, and a plurality of delivery valves, one in each delivery conduit, adapted each to be opened and shut by the variations in pressure in the interior 120 of the engine cylinder to which it is allotted, suction in each cylinder tending solely to open its allotted delivery valve, of fuel-supply controlling-means comprising a controlling member in said fuel-supply conduit, 125 130

and a suction device actuated by the joint suction of said cylinders and operatively connected with said controlling member, which controlling-means are arranged to 5 prevent the entry of as much fluid to the box as is evacuated therefrom while a delivery valve is open, and thereby cause a greater reduction of pressure in said box and in the

whole of each of said delivery conduits, when the delivery valve allotted thereto is 10 opened by suction, than would obtain were the said controlling means not provided, substantially as described.

In testimony whereof I affix my signature.

FREDERICK ARTHUR SMITH.
